UNITED STATES PATENT OFFICE.

WALTER RACHALS, OF YOUNGSTOWN, OHIO.

ROLLING-MILL.

1,283,299.

Specification of Letters Patent. Patented Oct. 29, 1918.

Application filed May 24, 1915. Serial No. 29,967.

To all whom it may concern:

Be it known that I, WALTER RACHALS, a citizen of the United States, residing at Youngstown, in the county of Mahoning and State of Ohio, have invented a new and useful Improvement in Rolling-Mills, of which the following is a full, clear, and exact description, reference being had to the accompanying drawings, forming part of this specification, in which—

Figure 1 is a front elevation of a portion of a rolling mill embodying my invention.

Fig. 2 is a vertical section taken longitudinally through the roll housing.

Fig. 3 is a transverse section on the line III—III of Fig. 2.

Fig. 4 is a vertical longitudinal section through the gear housing.

Fig. 5 is a plan view of the gear housing, and

Fig. 6 is a section on the line VI—VI of Fig. 4.

My invention has relation to an improvement in universal rolling mills.

One object of my invention is to provide an improved arrangement of the bearings for the top and bottom rolls of the mill so that the distance between bearings shall be a minimum; and also to provide means of simple and efficient character whereby the vertical rolls of the mill may be thrown out of action.

The nature of my invention will be best understood by reference to the accompanying drawings in which I have shown a preferred embodiment thereof, and which will now be described, it being premised, however, that various changes can be made in the details of construction and arrangement of the parts without departing from the spirit and scope of my invention, as defined in the appended claims.

In these drawings, the numeral 2 designates the mill housings and 3 the gear housing. 4 is the top roll of the universal mill, 5 the bottom roll and 6 the vertical rolls. 7 and 8 designate any suitable driving connections for the rolls 4 and 5, these being connected, respectively, to the shafts 9 and 10 journaled in the gear housing 3. The shaft 10 extends through said housing and may have any suitable driving connection. It is geared to the shaft 9 in any suitable way, such as the gears 11 (Figs. 4 and 6).

The vertical rolls 6 may be driven in any suitable manner. They are shown as having

bevel pinions 12 meshing with sliding pinions 13 on the parallel shafts 14, which extend within the gear housing 3 and carry therein pinions 15 driven by the intermediate idler pinion 16. The vertical rolls 6 are journaled in the movable carriages or carriers 17 mounted for travel on the tracks 18 on the housings 2 and are adjusted in any suitable manner, as by the shafts 19 which extend to the gear housing and are connected, respectively, to the motors 20 and 21 mounted on said housing. These shafts 19 are connected to the screws 22 through the gears 23.

Except in the particular hereinafter referred to, the parts, as thus far described, form no part of the present invention and are shown only for the purpose of completing the illustration.

The top roll 4 has its necks provided with the journal portions 24 which are journaled in bearings 25 seated in the windows of the housings 2 in the usual manner, and supported in any usual or suitable way, as by means of the hydraulic mechanism indicated at 26. Inside of the journal portions 24 and directly adjacent to the body of the roll 4 are other journal portions 27, which are mounted in bearings 28. The two bearings 28 are connected by a longitudinal bar 29 resting thereon and held by the two holding down screws 30, placed one directly over each bearing 28 and mounted in a yoke 31. These screws may be actuated by any suitable gearing, such as the bevel gearing shown at 30^a and driven from the motor 30^b. The bar 29, at its ends, extends into the windows of the main housings 2 and is guided therein.

A part of the space between the main housings being occupied by the vertical rolls and the connections for driving the same, it has been necessary heretofore to place the bearings for the top roll, together with the holding-down screws, within the plane of the housings. This has made the unsupported distance between the roll bearings considerably greater than actually required by the width of the piece to be rolled. It is, however, very important to have the unsupported distance between these bearings as short as possible, so that for a roll of given diameter it may have a maximum strength and a minimum deflection. By the provision of the auxiliary bearings 28, which are placed between the housings and as

closely to the ends of the body of the roll as the maximum width of the metal to be rolled will permit, I greatly reduce the unsupported distance between the bearings. The 5 horizontal forces caused by the friction between the upper roll and the bearings 28 is counteracted by the connecting bar 29. The usual bearings 25 in the windows of the housings take the horizontal thrusts due to 10 the momentum of the metal in entering the rolls.

The lower roll has single bearings 32 placed vertically in line with the bearings 28 for the top roll and carried by the yoke 33, which is rigidly fastened between the 15 lower portions of the housings 2 by the bolts 34. These lower roll bearings are in this manner also brought more closely together.

In the operation of a universal mill it 20 is sometimes advantageous to substitute grooved horizontal rolls in place of the cylindrical ones and to throw the vertical rolls out of action. In order to enable this to be done, I have shown the intermediate 25 idler gears 16 in the pinion housing as mounted in a vertical adjustable carrier 35 capable of being raised and lowered by means of the screw shafts 36. These shafts 30 may be actuated in any suitable manner, as by means of the lever and ratchet mechanism 37. When it is desired to throw the vertical rolls out of action, the idler 16 can be readily raised so that it will be thrown out of mesh with its driving pinion 11.

35 The advantages of my invention will be apparent to those familiar with universal mills, since it enables the unsupported distance between the bearings for the horizontal rolls to be reduced to a minimum consistent 40 with the maximum width of the pieces to be rolled. It also provides simple

and convenient means whereby the rolls can be thrown quickly out of action.

I claim:

1. A universal mill, having end housings 45 formed with windows and upper and lower horizontal rolls, the upper roll being supported for adjustment toward and away from the lower roll, upper roll bearings supported for vertical movement in said windows, auxiliary bearings for said upper roll located between the housings, a bar connecting the auxiliary bearings above the upper roll, and vertical holding-down screws 50 engaging said bar, substantially as described. 55

2. A universal mill, having end housings formed with windows and upper and lower horizontal rolls, the upper roll being supported for adjustment toward and away from the lower roll, upper roll bearings supported for vertical movement in said windows, auxiliary bearings for said upper roll located between the housings, a bar connecting the auxiliary bearings above the upper roll, and vertical holding-down screws 60 engaging said bar, the lower roll having bearings fixedly secured to the housings and located in vertical alinement with the auxiliary bearings of the upper roll, substantially as described. 65

3. A universal mill having end housings, and having its lower roll provided with bearings located between the said housings, and a yoke member carrying said bearings and fixedly secured to said housings; substantially as described. 70

In testimony whereof, I have hereunto set my hand.

WALTER RACHALS.
